United States Patent Office

Des. 188,870
Patented Sept. 20, 1960

188,870

LIPSTICK PACKAGE

Carl W. Middleton, Jr., Greenwich, Conn., and Earl Middleton, Pleasantville, N.Y.

Filed Sept. 18, 1959, Ser. No. 57,599

Term of patent 14 years

(Cl. D58—2)

Fig. 1.

Fig. 2.

Fig. 3.

Fig. 4.

Fig. 1 is a front elevational view of a lipstick package showing our new design;

Fig. 2 is a rear elevational view thereof;

Fig. 3 is a right side elevational view thereof; and

Fig. 4 is a lower end view of Fig. 1.

We claim:

The ornamental design for a lipstick package, substantially as shown.
